UNITED STATES PATENT OFFICE

JOHN F. OHMER, JR., OF DAYTON, OHIO, ASSIGNOR TO OHMER FARE REGISTER COMPANY, OF DAYTON, OHIO

PENNY-MULTIPLE REGISTER

Application filed March 23, 1922. Serial No. 545,941.

This invention relates to a penny multiple register for fares and the like and is in the nature of an improvement on the mechanism shown and described in the application for 5 patent filed by Ohmer and Kettman, on Feb. 8, 1922, Serial No. 535,039, which issued May 1, 1928 as Patent No. 1,668,024.

One object of the invention is to provide a machine which will register a relatively 10 large number of fares, or the like, in penny multiples by the manipulation of not more than two operating devices, and in which any selected fare within the capacity of the machine may be registered by a relatively small 15 amount of movement of the operating devices.

A further object of the invention is to provide a machine of this kind which will register both paper fares and cash fares and 20 which will register paper fares at their cash value.

A further object of the invention is to provide such a machine which will be simple in its construction and operation and which 25 will have no delicately adjusted parts or other mechanism which may be easily disarranged.

Other objects of the invention will appear as the mechanism is described in detail.

In the accompanying drawings Fig. 1 is a 30 front elevation of a registering mechanism embodying my invention; Fig. 2 is a sectional view taken on the line 2-2 of Fig. 1, and partially broken away; Fig. 3 is a detail view of one of the indicator gears; Fig. 4 is a detail view of one of the mutilated operating gears; Fig. 5 is a section taken on the line 5-5 of Fig. 1; Fig. 6 is a detail sectional view of the transfer mechanism taken on the line 6-6 of Fig. 9; Fig. 7 is a detail sectional view of 35 the transfer mechanism taken on the line 7-7 of Fig. 9; Fig. 8 is a section taken on the line 8-8 of Fig. 2; Fig. 9 is a section taken on the line 9-9 of Fig. 5; Fig. 10 is a sectional view similar to Fig. 2, partly broken away 40 and showing a modified form of the invention; and Fig. 11 is a front elevation of the mechanism of Fig. 10.

In these drawings I have illustrated one embodiment of the invention and have shown 45 the same as comprising an indicating mecha-

nism and a registering device, which in the present instance is of such a character that a printed record may be taken therefrom. This particular mechanism is designed to be embodied in the registering mechanism of 55 the above mentioned application and to be associated with the various other devices embodied in that application, but it will be understood that the mechanism here shown may be used with registering devices of various 60 kinds or that the indicating mechanism may be used alone, as, for example, an auxiliary indicator for a register.

In carrying out the invention I provide two 65 indicating devices, each of which consists of 70 two members, the members of each indicating device being adjustable relatively one to the other. Each indicating device is provided with a separate operating mechanism, the manipulation of which will actuate, or set, 75 either or both members of that indicating device. These indicating devices are indicated on the present drawings by the reference numerals A and B. The indicating device A, which may be termed the unit indicating device, or indicator, comprises two rotatable drums, or indicator wheels, 1 and 2, which are rotatable about a common axis and, as 80 here shown, are loosely mounted upon a shaft 3 mounted in a supporting frame 4. The indicator wheel 1 is the units wheel of the cash indicator and bears upon its periphery the numerals 0 to 9 inclusive. The indicator wheel 2, which may be called the ticket indicator, is for indicating paper fares, such as 85 tickets, half fares, school tickets, transfers, and the like, and it bears upon its periphery letters indicating the several classes of paper fares which are to be registered and may have none such indications thereon, the tenth space 90 being blank and corresponding to the zero indication on the units indicator wheel. This blank space is so arranged on the wheel that it will be adjacent to the sight opening in the casing when the indicator wheel or drum 95 2 is in its normal or idle position.

Suitable operating mechanism is provided for adjusting the two members of the units indicating device relatively one to the other so as to present at the sight opening, in the 100

casing which encloses the mechanism, an indication corresponding to the fare received. As here shown, this operating mechanism comprises a shaft 5 mounted in the frame 4 in the rear of the indicator wheels 1 and 2. This shaft may be rotated in any suitable manner, as by means of an actuating rod which is not here shown but which may be connected with the shaft 5 and may extend 10 lengthwise through the car above the seats where it may be conveniently operated by the conductor. Secured to each indicator wheel is a gear, 6 and 7, with which cooperates a driving, or operating, gear, 8 and 9, rigidly secured to the shaft 5. The indicator gears 6 and 7 are each provided with a peripheral recess 10 which may be formed by omitting one tooth of the gear. These recesses are so arranged with relation to the indications on 15 the indicator wheels that when the indicators are in zero positions the recesses in the corresponding gears will occupy positions adjacent to the operating gears 8 and 9, respectively. The operating gears 8 and 9 are 20 milled gears and are provided on one side with gear teeth which are sufficient in number to impart a complete rotation to the corresponding indicator gears. On the other side of its axis each of the operating gears has a 25 smooth periphery, as shown at 11, which is of such a radius that when the teeth of the gear have been moved out of mesh with the teeth of the corresponding indicator gear this smooth portion of the periphery will enter 30 the recess 10 in the indicator gear and thus lock the gear and its indicator against rotation. Both operating gears, 8 and 9, are identical in construction but are secured to the shaft 5 with their toothed portions on diametrically opposite sides of that shaft. Thus 35 it will be apparent that one complete rotation of the operating shaft will impart a complete rotation to both indicator wheels, the wheels being operated successively and the one being locked against rotation while the other 40 is being moved. It will be further apparent that the indicator wheels will be actuated by the rotation of the operating shaft in either direction, thus enabling the drums to 45 be rotated in that direction which will the most quickly bring the desired indication 50 into line with the sight opening.

As has been stated, the mechanism may, if desired, be provided with registering devices, other than the indicators, and, as here shown, I have provided printing wheels which will be set in the printing positions corresponding with the indicating positions of the respective indicator wheels and from 55 which a printed record may be taken, by suitable printing mechanism. Inasmuch as the printing mechanism of the above mentioned application, or any other suitable printing mechanism may be used, it is not necessary 60 to here illustrate the same as it forms no part

of this invention. The printing wheel for the ticket indicating wheel is shown at 12 and the printing wheel for the unit indicating wheel is shown at 13. These printing wheels are loosely mounted on the shaft 14 and each 70 has secured thereto a gear 15 which meshes with an intermediate gear 16 loosely mounted on a shaft 17 and these intermediate gears 16 in turn mesh with gears 18 and 19 mounted on the shaft 20. The gear 18 is thus connected with the ticket printing wheel and the gear 19 with the units printing wheel. Connected with the gear 18 is a gear 21 and connected with the gear 19 is a gear 22, the 75 gears 21 and 22 being also mounted on 80 the shaft 20 and being arranged for operation by the operating gears 8 and 9. The gears 21 and 22 are similar in construction and size to the indicator gears 6 and 7 and are provided with peripheral recesses similar to 85 those gears. In order that the printing wheels may be actuated simultaneously with the corresponding indicator wheels I have arranged the actuating mechanism for the 90 indicator wheels on that side of the operating shaft 5 opposite the indicator wheels and have so arranged the gearing that the printing ticket wheel will be actuated by the operating gear for the units indicating wheel and the units printing wheel will be operated by the operating gear for the ticket indicating wheel. To this end the gears 18 and 21 are rigidly secured to this shaft 20 and the gear 21 is arranged in cooperative 95 relation with the operating gear 8, while the 100 gears 19 and 22 are rotatably mounted on the shaft 20 and are connected by a sleeve 23, the gear 22 being arranged in cooperative relation with the operating gear 9. In this manner the operation of the operating shaft 5 105 will set both the indicating wheels of the units indicating device and the printing wheels corresponding thereto in positions to indicate and print, respectively, the same 110 item.

The indicating device B, which may be termed the tens and hundreds indicating device, also comprises two members, or indicating wheels, 24 and 25, which are adjustable relatively one to the other and are rotatable 115 about a common axis, these indicator wheels being, as here shown, mounted on the shaft 3. Operating mechanism is provided for setting these indicator wheels and this operating mechanism is independent of that which is 120 provided for the units indicating device. The indicating wheels 24 and 25 indicate respectively the tens and hundreds of the cash registrations and each is provided on its periphery with the numerals 0 to 9 inclusive. 125 Preferably, the tens indicator wheel 24 is initially operated and the count is transferred from that wheel to the hundreds indicator wheel 25. As here shown, this second operating device comprises a shaft 26 130

mounted in the frame 4 in the rear of the tens and hundreds indicator wheels and has rigidly secured thereto an operating gear 27 which meshes with a gear 28 rigidly secured to the tens indicator wheel 24. To transfer the count from the tens indicator wheel to the hundreds indicator wheel I have secured to the tens indicator wheel a gear 29 having on its periphery three teeth only which teeth are adapted to engage a twenty tooth gear 30 loosely mounted on the operating shaft 26. The three toothed gear 29 will, therefore, rotate the twenty tooth gear 30 through a space of four teeth or one-fifth of a revolution upon each complete rotation of the tens indicator wheel. Rigidly secured to the gear 30 and also loosely mounted on the shaft 26 is a second twenty tooth gear 31 which meshes with a forty tooth gear 32 rigidly secured to the hundreds indicator wheel 25. In this manner the forty tooth gear 32 and the hundreds indicator wheel will be rotated through one-tenth of a revolution for each complete revolution of the tens indicator wheel. In order that the transfer mechanism may be normally locked against movement during the operation of the tens indicator wheel I have also secured to the tens indicator wheel a locking disk 33 having in its periphery a recess 34 in which is arranged a single tooth 37. Cooperating with the locking disk 33 is a second locking disk, or gear, 35 loosely mounted on the shaft 26 and of the same size as the gears 30 and 31 with which it is rigidly connected. This locking member, or gear, 35 is provided with five groups of teeth, each group containing two teeth, as shown at 36, and it is so arranged with relation to the disk 33 that normally the peripheral edge of the disk will lie in the space between two groups of teeth, thereby locking the transfer mechanism against movement. When the tens indicator wheel completes its rotation and the teeth of the gear 29 engage the teeth of the gear 30 the peripheral edge of the disk 33 will be moved out of the recess in the gear 35 and the gear 35 will be permitted to rotate, the tooth 37 of the disk 33 entering the space between the two teeth of the adjacent pair of teeth 36 to permit of the relative movement of the parts.

The printing type wheels for the tens and hundreds are shown at 38 and 39 and are loosely mounted on the shaft 14. Connected with the tens printing wheel is a gear 40 which meshes with a gear 41 rigidly secured to the shaft 17. A second gear 42 on the shaft 17 meshes with an intermediate gear 43 which in turn meshes with the operating gear 27 for the tens indicating device. The ratio of gearing is such that the printing wheel 38 will be moved through an equal amount of rotation with the tens indicator wheel 24. The hundreds printing wheel has secured thereto a gear 44 which is provided with ten groups

of two teeth each, the groups of teeth being spaced apart. Rigidly secured to the shaft 17 is a one toothed gear 45 which will engage one pair of teeth on the gear 44 upon each rotation of the shaft 17, thereby causing the hundreds printing wheel to be advanced one-tenth of a revolution for each rotation of the shaft 17, while the tens printing wheel is advanced a complete revolution for each rotation of the shaft 17.

It will be noted that the indicator wheels are each provided with a recessed alining disk 46 with which cooperates a roller 47 carried by an arm 48. This alining device, however, is shown and described in the above mentioned application and forms no part of the present invention.

With the above described mechanism it will be apparent that before either the units indicator wheel or the ticket indicator wheel can be moved to indicating position the other indicating wheel of that indicating device must be moved to its zero, or neutral, position. It is sometimes desirable to indicate and register not only the particular paper fare which is received but the cash value of that fare. I have, therefore, shown in Figs. 10 and 11, a rearrangement of the operating mechanism for the unit indicating device which will permit the paper fare indicator wheel to be set to a selected position and the units indicator wheel then adjusted to any desired position with relation thereto. The tens and hundreds wheels can, of course, be adjusted to any desired position and I can, therefore, set the indicators and registers to indicate any desired paper fare and the money value of that fare. To accomplish this I have substituted for the operating mechanism for the units indicating device, as above described, an operating and transfer mechanism identical with that shown and described in connection with the tens and hundreds indicator wheels. A twenty toothed gear 49 is secured to the units indicator wheel 1 and meshes with a forty toothed gear 50 on the shaft 5, while a forty toothed wheel 51 is secured to the ticket wheel and meshes with the twenty toothed gear 52 of the transfer mechanism, which, as has been stated, is similar to that above described and it is not thought necessary to repeat the description thereof. With this arrangement of the mechanism I am able to indicate and register 999 cash fares and also to indicate and register 9 paper fares and 999 different cash values for each such paper fare. This large number of registrations may be effected by a relatively small amount of movement imparted to the mechanism through two operating devices.

The operation of the mechanism will be readily understood from the foregoing description of the several parts thereof, and it will be apparent that I have produced

a penny multiple indicator and register which will register a relatively large number of fares in penny multiples, as well as paper fares, by the manipulation of not more than 5 two operating devices and that the operating devices are of such a character that a relatively small amount of movement thereof will effect the desired indication. The mechanism is very simple in its construction, calls for no fine adjustments, and has 10 no parts which may be easily disarranged or rendered inoperative.

While I have shown and described one embodiment of my invention I wish it to be understood that I do not desire to be limited 15 to the details thereof as various modifications may occur to a person skilled in the art.

Having now fully described my invention what I claim as new and desire to secure by 20 Letters Patent, is:

1. In a mechanism of the character described, an indicator comprising two members separately rotatable about a common axis, a gear connected with each of said members, mutilated gears cooperating with the respective first mentioned gears, and means for simultaneously actuating said mutilated 25 gears, said mutilated gears being so arranged that they will successively engage the respective first mentioned gears.

2. In a mechanism of the character described, an indicator comprising two members separately rotatable about a common axis, a gear connected with each of said members, mutilated gears cooperating with the respective first mentioned gears, and means for simultaneously actuating said 35 mutilated gears, said cooperating gears being so arranged with relation to the two members of said indicator that one of said members will be moved to a neutral position before the other member is operated.

3. In a mechanism of the character described, an indicator comprising two members 45 separately rotatable about a common axis, a gear connected with each of said members, mutilated gears cooperating with the respective first mentioned gears, and means for simultaneously actuating said mutilated 50 gears, said cooperating gears being so arranged with relation to the two members of said indicator that one of said members will be moved to a neutral position before the other member is operated, and means for 55 retaining the first mentioned member in its neutral position during the operation of said other member.

4. In a mechanism of the character described, an indicator comprising two members 60 separately rotatable about a common axis, a gear connected with each of said members, mutilated gears cooperating with the respective first mentioned gears, and means for simultaneously actuating said 65 mutilated gears, said mutilated gears being

so arranged that they will successively engage the respective first mentioned gears, each of said mutilated gears having a part to engage the corresponding first mentioned gear to hold the latter against movement when said mutilated gear is out of engagement therewith. 70

5. In a mechanism of the character described, an indicator comprising two members separately rotatable about a common axis, a gear connected with each of said members, each of said gears having a peripheral recess, mutilated gears cooperating with the respective first mentioned gears, and means for simultaneously actuating said mutilated 75 gears, each of said mutilated gears having a part concentric with its axis and arranged to enter the recess in the corresponding first mentioned gear when the teeth of said mutilated gear are out of engagement therewith. 80

6. In a mechanism of the character described, an indicator comprising two members separately rotatable about a common axis, a gear connected with each of said members each of said gears having a peripheral recess, two circular driving members mounted on a common axis, means for rotating said driving members in unison, each of said driving members having a portion of its periphery provided with teeth to engage the corresponding first mentioned gear and having another portion of its periphery smooth and concentric with its axis and arranged to enter the recess in the corresponding first mentioned gear, the toothed portions of said driving members being out of line one with the other. 95

7. In a mechanism of the character described, an indicator comprising two members separately rotatable about a common axis, a gear connected with each of said members, each of said gears having a peripheral recess, two circular driving members mounted on a common axis, means for rotating said driving members in unison, each of said 100 driving members having approximately one-half its periphery provided with teeth to engage the corresponding first mentioned gear and having the remainder of its periphery smooth and arranged to enter the recess in the first mentioned gear when the toothed portion of said driving member is out of engagement therewith, the toothed portions of the two driving members being located on opposite sides of the common axis of said driving members. 115

8. In a mechanism of the character described, an indicator comprising two members separately rotatable about a common axis, a single operating device comprising two driving members for successively actuating the respective members of said indicator, a fare registering device comprising a registering wheel corresponding to each member of said 120 125 130

- indicator; and means operated by said driving members to actuate said register wheels, corresponding to the respective indicating members; and a gear connected with each register wheel and having a recess, the gears for said register wheels being so arranged with relation to said driving members that the gear for one register wheel will be engaged by the teeth of the driving member for the indicating member corresponding to the other of said register wheels while the smooth portion of said driving member is in the recess of the gear for said indicating member.
9. In a mechanism of the character described, an indicator comprising two members separately rotatable about a common axis, a single operating device comprising two driving members for successively actuating the respective members of said indicator, a fare registering device comprising a registering wheel corresponding to each member of said indicator, and means operated by the driving member for one indicating member to actuate the register wheel corresponding to the other indicating member.
10. In a mechanism of the character described, an indicator comprising two members separately rotatable about a common axis, a gear connected with each of said members, mutilated gears cooperating with the respective first mentioned gears, means for simultaneously actuating said mutilated gears, said mutilated gears being so arranged that they will successively engage the respective first mentioned gears, register wheels corresponding to the respective members of said indicator, and a gear connected with each register wheel and arranged to be actuated by one of said mutilated gears.
11. In a mechanism of the character described, an indicator comprising two members separately rotatable about a common axis, a gear connected with each of said members, mutilated gears cooperating with the respective first mentioned gears, means for simultaneously actuating said mutilated gears, said mutilated gears being so arranged that they will successively engage the respective first mentioned gears, register wheels corresponding to the respective members of said indicator, and a gear connected with each register wheel and arranged to be actuated by one of said mutilated gears, the gear for one of said register wheels being arranged to be engaged by the mutilated gear for the indicating member corresponding to the other of said register wheels.
12. In a mechanism of the character described, an indicator comprising two members separately rotatable about a common axis, a gear connected with each of said members, each of said gears having a peripheral recess, two circular driving members mounted on a common axis, means for rotating said driving members in unison, each of said driving members having approximately one-half its periphery provided with teeth to engage the corresponding first mentioned gear and having the remainder of its periphery smooth and arranged to enter the recess in said first mentioned gear when the toothed portion of said driving member is out of engagement therewith, the toothed portions of the two driving members being located on opposite sides of the common axis of said driving members, register wheels corresponding to the respective indicating members and means operated by the driving member for one indicating member to actuate the register wheel corresponding to the other indicating member.
13. In a mechanism of the character described, an indicator comprising two separately operable indicating devices, one of said indicating devices having a member carrying units indications and a second member carrying paper fare indications, said members being separately rotatable, the other indicating device having a member carrying tens indications and a second member carrying hundreds indications, means for transferring the count from the tens indicating member to the hundreds indicating member, an operating device connected with said tens indicating member, a second operating device connected with said units indicating member and said paper fare indicating member, and having means for successively actuating said units indicating member and said paper fare indicating member.
14. In a mechanism of the character described, a penny multiple indicator comprising two separately operable indicating devices, each indicating device comprising two members which are adjustable relatively one to the other, separate operating devices for the respective indicating devices, means actuated by one of said operating devices for moving one of said members in either direction, and means controlled by the first mentioned member for moving a second member in the same direction.
15. In a mechanism of the character described, two separately operable indicating devices, each comprising two members, the members of each indicating device being adjustable relatively one to the other, separate operating devices for the respective indicating devices, and means actuated by said operating devices for setting one member of one of said indicating devices in a predetermined position and adjusting the other members of both indicating devices relatively to the first mentioned member.
16. In a mechanism of the character described, two separately operable indicating devices, each comprising two indicator wheels, the indicator wheels of each indicating device being adjustable relatively one to the other, the indicator wheels of one indicating device having respectively paper fare indications and unit indications and the indicator wheels of the other indicating device having respectively tens indications and hundreds indications, separate operating

devices for the respective indicating devices, and means actuated by said operating devices for moving the paper fare indicating wheel into a predetermined position and 5 adjusting the other indicating wheels relatively thereto.

17. In a mechanism of the character described, an indicator comprising two members separately rotatable in either direction about a common axis, and a single operating device having separate connection with the respective members and the continuous movement of which in either direction will successively actuate said members. 10

18. A penny multiple indicator comprising two separately operable indicating devices, one of said indicating devices comprising two members, each separately movable with relation to the other, and arranged 15 to cooperate with the other indicating device to indicate in penny multiples an item comprising three digits, a single operating device for said indicating device having means for selectively actuating either member thereof, and for holding the other member 20 against movement during the movement of the member which is actuated, and means for actuating the other indicating device. 25

19. In a mechanism of the character described, a penny multiple indicator comprising two separately operable indicating devices, one of said indicating devices comprising two members each separately movable 30 with relation to the other, and arranged to cooperate with the other indicating device to indicate in penny multiples an item comprising three digits, a single operating device for said indicating device having means for first 35 moving one of said members to its neutral position and then actuating the other member, and means for actuating the other indicating device. 40

20. In a mechanism of the character described, a penny multiple indicator comprising two separately operable indicating devices, one of said indicating devices comprising two members each separately movable 45 with relation to the other, and arranged to cooperate with the other indicating device to indicate in penny multiples an item comprising three digits, a single operating device for said indicating device, the continuous movement of which in one direction will first 50 move one of said members to its neutral position and then move the other of said members to a selected position, and means for operating the other indicating device. 55

21. In a mechanism of the character described, a penny multiple indicator comprising two separately operable indicating devices, one of said indicating devices comprising two members each separately movable 60 with relation to the other, and arranged to 65 cooperate with the other indicating device

to indicate in penny multiples an item comprising three digits, a single operating device for said indicating device having means for first moving one of said members to its neutral position, locking the same in that position 70 and then actuating the other member, and means for operating the other indicating device. 75

22. In a mechanism of the character described, an indicator comprising two members separately rotatable about a common axis to selected positions with relation one to the other, and a single operating device for selectively positioning said members, said operating devices having means for moving either of said members to its selected position 80 and for holding the other member against movement. 85

23. In a mechanism of the character described, an indicator comprising two members separately rotatable about a common axis to selected positions with relation one to the other, and a single operating device for selectively positioning said members, said operating device having means for moving either of said members to a neutral position 90 and then moving the other member to a selected position. 95

24. In a mechanism of the character described, a fare indicator comprising two separately operable indicating devices, one of said indicating devices having a member carrying units indications and a second member carrying paper fare indications, said members being separately operable, the other indicating device having a member carrying tens indications and a second member carrying hundreds indications, said units, tens and hundreds indicating members being arranged 100 to indicate in penny multiples a selected item comprising three digits, and a single operating mechanism for each of said indicating devices, said operating mechanisms being separate one from the other. 105

25. In a mechanism of the character described, a fare indicator comprising two separately operable indicating devices, one of said indicating devices having a member carrying units indications and a second member carrying paper fare indications, said members being separately rotatable, the other indicating device having a member carrying tens indications and a second member carrying hundreds indications, said units, tens and hundreds indicating members being arranged 110 to indicate in penny multiples a selected item comprising three digits, a single operating mechanism for each of said indicating devices, said operating devices being separate one from the other, printing wheels corresponding to the members of said indicating devices, and means actuated by said actuating devices for setting said printing wheels to print a record of the item indicated by the respective indicating devices. 115 120 125 130

26. In a penny multiple indicator, an indicator shaft and an operating shaft arranged in parallel relation, an indicating device mounted on said indicator shaft and comprising two members which are adjustable relatively one to the other, means actuated by said actuating shaft to adjust one of said members, a mutilated gear rigidly connected with said member for rotation therewith
- 5 about the axis of said indicator shaft, a second gear rotatably mounted on said actuating shaft and arranged to be actuated by said mutilated gear through a predetermined movement upon each complete rotation of
- 10 said member, a third gear rotatably mounted on said actuating shaft and rigidly connected with said second gear, a fourth gear rigidly connected with the other member of said indicating device for rotation therewith
- 15
- 20 about the axis of said indicator shaft and meshing with said third gear, and cooperating members rigidly connected respectively with said mutilated gear and with said second gear.
- 25 In testimony whereof, I affix my signature hereto.
